INVENTOR

UNITED STATES PATENT OFFICE.

CHRISTOPHER C. JONES, OF CHIPLEY, GEORGIA.

MOLD FORM.

Application filed June 23, 1922. Serial No. 331,672.

To all whom it may concern:

Be it known that I, CHRISTOPHER C. Jones, a citizen of the United States, residing at Chipley, in the county of Harris and State of Georgia, have invented new and useful Improvements in Mold Forms, of which the following is a specification.

This invention relates to a form for molding caskets and similar objects, the principal object of the invention being to provide a form which may be easily and quickly separated from the molded object without destroying any parts of the form so that the same can be used again for molding other objects.

Another object of the invention is to provide means whereby the interior part of the form can be contracted to facilitate its removal from the interior of the casket.

Still another object of the invention is to provide both the interior and exterior parts of the form with separable side and end walls and corner pieces with means for detachably connecting the side and end walls to the corner pieces.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of a form constructed in accordance with my invention.

Figure 2 is a plan view with parts broken away.

Figure 3 is an elevation of the interior part of form.

Figure 4 is a section on line 4—4 of Figure 2.

Figure 5 is a section on line 5—5 of Figure 2.

Figure 6 is an end view.

Figure 7 is a section on line 7—7 of Figure 1.

Figure 8 is a view of one of the corner pieces for the exterior part of the form.

Figure 9 is a view of one of the corner pieces for the interior part thereof.

Figure 10 is a view of one of the members for contracting the interior part of the form.

In these views A indicates the exterior part of the form and B the interior part. The part A comprises the two side pieces 1, the two end pieces 2 and the four corner pieces 3. The form may be made of any suitable material though the drawings show the side and end pieces being formed of sheet metal 4 reenforced by the horizontal bars 5 and the vertical bars 6, the middle horizontal bar 5 being of T-shape in cross section while the other bars are of angle shape. A substantially L-shaped casting 7 is arranged at each end of each side and end piece and the horizontal bars 5 are connected with these castings. Each corner piece 3 is formed with the wings 3' and the diagonal piece 3'' which connects the wings together. The wings carry the staples 3' which are adapted to pass through slots 7' formed in the castings 7 and to receive pins 8 and which engage lugs 7'' formed on the outer face of each casting 7. The wings 3' of the corner pieces will engage the recesses formed by the L-shape of the castings, as shown clearly in Figures 2 and 7. By this arrangement of parts the sides and end pieces are firmly secured to the corner pieces and the parts can be easily and quickly separated by removing the pins 8.

The interior part B is constructed similarly to the outer part though the reenforcing bars and castings and their associated parts are arranged on the interior faces instead of upon the outer faces as upon the outer part. The portions of this interior part are each provided with an outwardly extending flange 9 at its bottom which extends into the molding space C formed by the two parts of the mold while the bottom portion of each part of the exterior mold is curved outwardly, as at 10, in order to give the casket a thickened upper edge, the outer face of which curves outwardly from the body part. The flange 9 forms a recess in this upper edge of the casket for receiving the cover part of said casket.

In order to form the bottom of the casket cross bars 11 are arranged across the top of the interior form with their ends resting upon the upper horizontal bar and plates 12 are placed on these cross pieces, said plates covering the open top of the interior part of the mold. As will be seen from Figures 4 and 5 the interior part of the mold is of less depth than the exterior part so that the plates 12 will be spaced from

the upper edge of the exterior part so that after the vertical parts of the molding space C is filled with the molding material, the horizontal space formed by plates 12 is 5 filled so as to form the bottom of the casket. Before starting the molding action the mold is placed upon a base 13 which encloses the bottom of the molding space. After the cast has set the mold is turned over 10 so as to expose the interior part of the form. The hooked ends of bars 14 are then inserted in holes 15 formed in the horizontal bars 5 and the turn buckles 16, which connect the pairs of bars together are rotated to shorten 15 the pairs of bars to contract the interior part. The turn buckles of the bars which connect the sides of the form together are first manipulated so as to draw the two sides towards each other. As will be seen 20 from Figure 2 the cross bars 11 have their ends spaced from the plates 4 of the sides so as to permit this movement of the sides and I place strips 17 of cardboard or the like between the abutting surfaces of the corner 25 pieces and side and end pieces to permit movement of the side pieces and the corner pieces. It will of course be understood that the pins are removed from the staples before the turn buckles are moved. After this 30 movement of the sides they can be lifted out and then the turn buckle arrangement for the end pieces can be put in place to draw the end pieces and corner pieces away from the ends of the molded article. In 35 order to facilitate this movement of the end pieces and corner pieces I slightly bevel each corner piece, as at 18, so as to make the ends of the interior part of the mold of less length

than the width of the casket. After these end pieces have been moved away from the ends 40 of the casket they can be removed and the cross pieces 11 and the plates 12 can be taken out. the exterior part of the form can then be removed by simply removing the pins to permit the parts to be separated. 45

This mold will form a casket in one piece with smooth walls, the upper edge of which is thickened and provided with an interior recess to receive a cover plate and the interior and exterior corners of which are beveled instead of being squared. 50

My form can be used over and over again as none of the parts thereof are destroyed in removing the form from the cast.

It is thought from the foregoing description that the advantages and novel features of my invention will be readily apparent. 55

I desire it to be understood that I may make changes in the construction and in the combination and arrangement of the several 60 parts, provided that such changes fall within the scope of the appended claim.

What I claim is:—

A mold of the class described comprising 65 interior and exterior members, each member consisting of side and end pieces and corner pieces, said side and end pieces having recesses therein for receiving parts of the corner pieces, lugs at the ends of the side and end pieces and said pieces having notches 70 in their ends adjacent the lugs, staples on the corner pieces engaging said notches and pins for engaging the staples and resting against the lugs.

In testimony whereof I affix my signature.
CHRISTOPHER C. JONES.
